ATTORNEY

UNITED STATES PATENT OFFICE

JOHN B. BROUGHTON, OF WICHITA FALLS, TEXAS

TERMINAL TOOL

Application filed March 28, 1928. Serial No. 265,415.

This invention relates to a tool for removing clamps from battery terminals, the general object of the invention being to provide means for gripping the clamp and at the same time applying pressure to the terminal to force the clamp from the terminal.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an elevation with one of the plates removed.

Figure 2 is a view showing the device in use.

Figure 3 is a section on line 3—3 of Figure 1.

In these views, the numeral 1 indicates a handle member which is formed with a jaw 2 and the numeral 3 indicates a pair of plates fastened to the intermediate part of the member 1, one on each side thereof. A jaw 4 is pivoted between the plates and a handle 5 is also pivoted between the plates, the jaw 4 and the handle 5 being connected to the plates at the sides thereof opposite to the sides to which the member 1 is connected. A rack bar 6 is slidably arranged in the space between the plates formed by the handles and the handle 5 has its inner end enlarged and provided with the teeth 7 for engaging the teeth of the rack 6. The lower end of the rack 6 forms a plunger 8.

In using the device, the handle 5 is moved outwardly so as to raise the plunger and the jaws 2 and 4 placed in engagement with the clamp 9 which is to be removed from the terminal 10 of the battery B. Then the handles are moved toward each other so that the toothed portion of the handle 5 will cause the plunger 6 to move downwardly against the top of the terminal 10 and thus cause the jaws 2 to pull the clamp from the terminal 10.

nal so that the clamp can be easily and quickly removed.

It is thought from the foregoing description that the advantages and novel features of my invention will be readily apparent.

It is to be understood that I may make changes in the construction and in the combination and arrangement of the several parts, provided that such changes fall within the scope of the appended claims.

What I claim is:

1. A tool of the class described comprising a handle member having a jaw at one end thereof, a pair of plates connected with the intermediate portion of the handle member, one on each side thereof, a jaw pivoted between the plates and depending therefrom and arranged opposite the stationary jaw, a handle pivoted between the plates above the pivoted jaw, a plunger slidably arranged between the plates and slidably engaging the intermediate portion of the handle member and means for moving the plunger by the movement of the second handle toward the first handle.

2. A tool of the class described comprising a handle member having a jaw at one end thereof, a pair of plates connected with the intermediate portion of the handle member, one on each side thereof, a jaw pivoted between the plates and depending therefrom and arranged opposite the stationary jaw, a handle pivoted between the plates above the pivoted jaw, and having its inner end enlarged and provided with teeth, a plunger slidably arranged between the plates and slidably engaging the intermediate portion of the handle member and having teeth thereon for engaging the teeth of the second handle so that when the second handle is moved toward the first handle, the plunger will be projected.

In testimony whereof I affix my signature.

JOHN B. BROUGHTON.
